UNITED STATES PATENT OFFICE.

MANLEY KELLEY, OF COLO, IOWA.

CENTRIFUGAL CREAM-SEPARATOR.

No. 815,094.

Specification of Letters Patent.

Patented March 13, 1906.

Application filed April 14, 1905. Serial No. 255,585.

To all whom it may concern:

Be it known that I, MANLEY KELLEY, a citizen of the United States, residing at Colo, in the county of Story and State of Iowa, have invented certain new and useful Improvements in Centrifugal Cream-Separators, of which the following is a specification.

This invention relates to cream-separators of the centrifugal type, and is comprised mainly in the special means employed for effecting thorough and complete separation of the cream-globules from the heavier watery portions of the liquid introduced into the bowl of the separator. The means comprising this invention aims to facilitate the separating operation, so as to increase the capacity of the machine to the greatest extent practicable.

For a full description of the invention and the merits thereof and also to acquire a knowledge of the details of construction of the means for effecting the result reference is to be had to the following description and accompanying drawings, in which—

Figure 1 is a vertical sectional view showing a separator-bowl having the invention applied thereto. Fig. 2 is a view similar to Fig. 3 embodying a modification. Fig. 3 is a detail perspective view of a set of coils such as are used in the construction in Fig. 1. Fig. 4 is a perspective view similar to Fig. 3, the set of coils illustrated being of the form used in the construction in Fig. 2. Fig. 5 is a broken sectional view embodying a further modification.

Corresponding and like parts are referred to in the following description and indicated in all the views of the drawings by the same reference characters.

Referring to the drawings, the numeral 1 indicates the bowl of a centrifugal separator, said bowl being of any conventional and approved construction at present in use. The feed-tube 2 enters the bowl 1 and is provided at its lower portion with the lateral outlets 3, as is customary. The separating-bowl 1 is provided at its upper portion with the skimmed-milk outlet-passages 4 and the cream-outlet 5 above the passages 4.

Arranged within the body of the bowl 1 are a plurality of coils 6 6^a 6^b 6^c, &c., arranged in sets, said sets of coils being arranged one

within the other and concentrically of the tube 2, through which the liquid is fed into the bowl. The term "coils" as used herein is designed as a broad or generic term applying to rings, coils, or similar parts arranged and combined in a manner herein specified for accomplishing the functions of the invention. In the preferred form of the invention the sets of coils 6 6^a, &c., are arranged in spaced relation and the various coils of each set are in vertical alinement, so that vertical passages 7 are formed between the sets of coils. Further, the coils of each set of coils 6^a which are in superposed relation are spaced from each other to a certain extent, the adjacent coils of the sets of coils 6 6^a 6^b, &c., being spaced vertically, forming lateral passages 8, leading from the central portion of the bowl toward the outer wall thereof. The coils of the adjacent sets of coils are in both vertical and lateral alinement, so as to provide the passages 7 and 8 aforesaid, and the sets of coils are preferably made of a single length of metal, such as wire of a suitable size bent spirally in the preferred form of the invention, as shown in Figs. 1 and 2, to form the various sets of coils aforesaid. The coils of each set of coils 6 6^a 6^b, &c., are preferably attached together by means of vertical bars 9, curved to form hooks at opposite ends to engage over the uppermost and lowermost coil of each set. The bars 9 are preferably attached exterior of the sets of coils, and when the various sets are arranged one within the other said bars 9 form spacing members between the sets of coils to facilitate the provision of the passages 7 and at the same time assist in promoting the separation of the cream-globules from the watery or skimmed liquid. The sets of coils 6 6^a, &c., may be made of independent or separate coils, if desired, within the contemplation of the invention, though the construction above mentioned is preferably utilized. The material from which the sets of coils are preferably made, being of circular formation in cross-section facilitates the passage of the liquid from the central to the outermost portion of the bowl 1 in the separating action of the machine. The various sets of coils are of course separate, preferably, so as to facilitate cleansing thereof, the arrangement of the coils be-

ing such that when the sets are disposed in the bowl 1 the same are held in their proper position by contact with each other and in compact relation. The number of sets of 5 coils employed is immaterial, since such number may be varied according to the best results attained in the actual use of the machine.

The operation and advantages of the invention will now be noted. As the bowl 1 revolves in the customary manner the liquid passing into the bowl through the tube 2 will be thrown outwardly by centrifugal action and the watery and heavier portions of the 15 liquid will quickly pass through the passages 8 to the outermost portion of the bowl, escaping from the latter through the outlet-passages 4. The cream-globules, however, pass upwardly through the various passages 7 at 20 distances from the center of the bowl dependent upon the point of separation of said globules from the skimmed or watery portions of the liquid. However, it will be seen that the plurality of passages 7 will permit 25 the cream-globules to separate at various points, and the coils of the various sets of coils in the arrangement described greatly facilitate the separation of the cream-globules, so that the latter are free to rise in a 30 manner which will be apparent to those versed in this art. The cream-globules of course pass from the bowl 1 through the cream-outlet 5.

Figs. 2 and 4 illustrate a modification of 35 the invention in which the laterally-alined coils are arranged in sets, (indicated at 10 10^a 10^b 10^c, &c.,) the sets being placed one above the other with the coils thereof in vertical and lateral alinement. The sets of coils 10 40 10^a, &c., however, are preferably made of conical form, the material from which they are constructed being wound helically instead of spirally, as indicated in connection with the construction of Figs. 1 and 2. The coils 45 of the sets 10 10^a, &c., are secured together in any suitable way, and the spaced relation of the coils of each set and of the sets of coils is substantially the same as indicated with reference to the preferred construction before 50 described. The form of the sets of coils 10 10^a, &c., is such that the passages 1^a, which extend with the passages 8 in Fig. 1, are inclined downwardly instead of horizontally. The above is advantageous under certain 55 conditions in separating the cream-globules from the milk, the liquid being forced downwardly instead of horizontally as it passes through the passages 8. The passages 7^a in Fig. 2 are the same as those indicated at 7 in 60 Fig. 1. The sets of coils 10 10^a, &c., may be reversed, as shown in Fig. 5, so that the passages 8^a will incline upwardly instead of downwardly, this being advantageous under certain conditions also.

Having thus described the invention, what 65 is claimed as new is—

1. In a centrifugal cream-separator, the combination of a separating-bowl, and spaced inner and outer coils in said bowl.

2. In a centrifugal cream-separator, the 70 combination of a separating-bowl, and spaced sets of inner and outer superposed coils in said bowl, the coils of each set being spaced from each other.

3. In a centrifugal cream-separator, the 75 combination of a separating-bowl, and sets of inner and outer spaced coils in said bowl, the coils of each set being of approximately circular formation in cross-section.

4. In a centrifugal cream-separator, the 80 combination of a separating-bowl, and sets of inner and outer coils in said bowl, the sets of coils being so arranged as to form outflow-passages therebetween.

5. In a centrifugal cream-separator, the 85 combination of a separating-bowl, and sets of inner and outer coils in said bowl, the sets of coils being so arranged as to form vertical outflow-spaces therebetween, the relative positions of the coils of each set being such as 90 to form lateral outflow spaces or passages.

6. In a centrifugal cream-separator, the combination of a separating-bowl, and sets of inner and outer coils in said bowl, the sets of coils being so arranged as to form vertical 95 outflow-spaces therebetween, the relative positions of the coils of each set with regard to the coils of the next adjacent set, being such as to form straight lateral outflow-passages.

7. In a centrifugal cream-separator, the combination of a separating-bowl, and sets of inner and outer concentric spaced coils in 100 said bowl.

8. In a centrifugal cream-separator, the 105 combination of a separating-bowl, sets of inner and outer concentric spaced coils in said bowl, and a feed-tube entering the bowl centrally of the innermost set of coils.

9. In a centrifugal cream-separator, the 110 combination of a separating-bowl, sets of coils in said bowl, and spacing means between the sets of coils.

10. In a centrifugal cream-separator, the combination of a separating-bowl, and sets 115 of coils in said bowl, each set being made of a single length of material.

11. In a centrifugal cream-separator, the combination of a separating-bowl, sets of coils disposed in the bowl, and bars connecting the coils of each set.

In testimony whereof I affix my signature in presence of two witnesses.
